UNITED STATES PATENT OFFICE.

WALLACE W. HANLON, OF CHATTANOOGA, TENNESSEE, ASSIGNOR TO CHATTANOOGA ROOFING & FOUNDRY COMPANY, OF CHATTANOOGA, TENNESSEE, A CORPORATION OF TENNESSEE.

FIREPLACE BASKET.

Application filed November 20, 1924. Serial No. 751,175.

To all whom it may concern:

Be it known that I, WALLACE W. HANLON, a citizen of the United States of America, residing at Chattanooga, county of Hamilton, State of Tennessee, have invented certain new and useful Improvements in Fireplace Baskets; and I do hereby declare that the following is a full, clear, concise, and exact description of the invention, such as will enable others skilled in the art to which it appertains to make and use the same.

This invention relates to improvements in fire-place baskets of such construction as will permit the adoption or connection of the same to any form of grate frame now prevalent in the art, without alteration or modification of the latter in any way.

It is well known in this art that those forms or designs of fire-places employing grate frames for the dual purpose of ornamentation and supporting fire baskets or grates are equipped with supporting lugs differing in arrangement and disposition with the products of various competing manufacturers. Thus, it often times occurs that the fire basket of one manufacturer cannot be used in connection with or fitted upon the grate or basket frame of another manufacturer and vice versa. In consequence of this unfortunate and impractical condition, a user of a particular form of fire-place equipment aforesaid, is frequently handicapped in the replacement of broken or worn portions thereof, and also, there are instances where a user of such equipment is required to make extensive outlay for such equipment, as where a portion of his broken or worn equipment is purchased from one concern might be replaced at a cost less than the original through the purchase of such equipment produced by another concern.

In sequence with the fore-going, it may be stated that it is a more specific object of my invention to provide a fire-place grate or basket which is universally adaptable to any form of frame now being marketed, without alteration thereto in any way whatsoever.

Other objects of the invention will be in part obvious, and in part pointed out herein-after.

In order that the invention and its mode of adaptation may be readily understood by persons skilled in the art, I have in the accompanying illustrative drawings, and in the detailed following description based

thereon, set out one possible embodiment of the same.

In these drawings:

Figure 1 is a front elevation of a fireplace equipped with my improved form of basket;

Figure 2 is a horizontal section taken on the line 2—2 of Figure 1, looking in the direction in which the arrows point;

Figure 3 is an enlarged vertical section taken on the line 3—3 of the Figure 1, looking in the direction in which the arrows point; and,

Figure 4 is an enlarged fragmentary detail in vertical section, taken on the line 4—4 of the Figure 2, looking in the direction in which the arrows point.

Having more particular reference to the drawings, in connection with which like characters of reference will designate corresponding parts throughout, the improved basket, as stated, is universally adaptable to any form or design or make of fire-place grate frame now prevalent in the art and for purposes of illustration of this invention, I have chosen one form of grate frame, indicating the same, in its entirety, by the numeral 1. Extending inwardly from the inner marginal portion of the opposite sides of the grate frame 1 are pairs of supporting lugs indicated for the purpose of convenience by the numeral 2, it being the function of these lugs to receive brackets, hooks, arms, or other attaching and supporting devices provided upon the particular form of design of fire baskets going with the equipment. In the production of these grate frames 1, a certain peculiar condition is often experienced, in that the fire basket supporting lugs 2 differ in their arrangement and disposition quite frequently upon the products of different and competing manufacturers. In consequence upon this peculiarity, it frequently happens that the fire basket of one concern cannot be used or fitted upon the grate frame of another concern because of the fact that the attaching devices of the fire basket differ in their arrangement, construction and formation.

To overcome the above noted disadvantages, it is proposed by this invention to provide a fire-place basket of a universal nature, that is, a fire-place basket having attaching devices which may be successfully and practically engaged or connected with

the supporting lugs 2 of any form of grate frame now prevalent in the art. To this end, the invention may be stated to comprise a fire basket including the usual front or front wall made up of bars as indicated by the numeral 3 of foraminated or reticulated metal, such as conditions or preference may dictate, curved grate bars 4 extending from and being supported upon the 10 lower side of said front whereby to provide the fire receiving and retaining grate. This construction, as will be well understood by workers skilled in the art, is common and well known in the art and therefore, it is to be understood that the particular construction or design of front and fire grate may be varied and yet, well remain within the province of this invention.

With a view towards providing the fire-place basket with attaching means whereby it can be connected to the supporting lugs of any form of grate frame, irrespective of its design of manufacture, such as indicated herein by the numeral 1, I form or arrange upon the opposite side and vertical portions of the front 3, channeled lug receiving brackets indicated in their entireties for the purpose of convenience herein by the numeral 5, said brackets 5 being 25 formed or cast integral with the vertical oppositely disposed sides of the front 3 as is clearly shown in the Figures 2 and 4 and having the lug receiving ways therein of a depth sufficient to permit of positive reception or engagement of the free or outwardly extended portions of said lugs therein, as is also clearly shown in the Figures 1, 2 and 4. The width of the lug receiving ways in the brackets 5, it may be noted, is also of such dimension as to permit of free engagement of practically any form of fire place front or basket supporting lugs now manufactured and marketed, therein. The lower portions of the inner sides of the brackets 5 are cut away as indicated at 5^a and by reason of this opening to the ways of the several brackets 5, it will be understood that the lugs 2 may be effectually introduced and engaged in their proper positions within such bracket; 40 5. In this connection, it will be noted upon reference to the Figure 4 that with engagement of the lugs 2 in the ways of the vertically arranged and oppositely disposed brackets 5, the uppermost lug will contact 45 with the closed upper end of its respective bracket 5 whereas the lower lug will be engaged in the intermediate or lower portion of its respective bracket 5 and in consequence, will exert or effect a staying and 50 bracing of the improved fire place basket with respect to the frame 1; that is, material outward or lateral movement of the basket with respect to the frame will be prevented, in that the upper supporting lug 2 will provide the supporting engagement as between

the fire place basket and the frame, whereas the lower lug 2 will serve to prevent swinging of the bracket carrying portions 5 of said basket upon the aforesaid upper lugs 2. By consequence, it is to be appreciated that any possibility of accidental or undue displacement of the basket through lateral movement as hereinbefore explained will be prevented.

Due to the fact that the brackets 5 formed upon the outer sides of the opposed vertically arranged basket sides are formed with their elongated ways as is clearly shown in the Figure 3, it will be appreciated that the same may be effectually engaged with practically any arrangement of basket supporting lugs upon those forms of fire place grate supporting frames now prevalent in the art, variance in the placement of such lugs being immaterial as regards the practical supporting of the improved fire place basket in that the uppermost of such lugs will serve as the supporting means, whereas the lower lugs, irrespective of their placement or distance from the upper lugs, will serve as a staying and bracing means for the basket, preventing material lateral swinging, swaying, or other similar movement thereof with respect to the frame, and hence, ensuring proper positioning of the fire place basket with respect to such frame at all times.

In constructing the improved fire-place basket, the length of the grate composed of the bars 4 is slightly less than the distance occurring between the inner marginal portions of the opposite sides of the grate frame 1 and likewise, slightly less than the distance between the outermost ends of the several pairs of oppositely disposed supporting lugs 2. Because of this, it will be understood that that vertical movement of the basket necessary in its being fitted or connected to the grate frame 1 and by the pairs of lugs 2 will be permitted. In bringing about this particular condition, the opposite ends of the grate front 3 are preferably curved inwardly as shown at 6, so that while the grate of the fire place basket will be of a length slightly less than the width of the opening provided by the grate frame 1, the front thereof will be of an approximately corresponding width and hence, will completely span the distance between the inner marginal portion of the opposite sides of the grate frame 1, as is clearly shown in the Figure 1, thus lending to the practicability as well as the ornamental appearance of the equipment. Furthermore, this particular formation of the grate with respect to the front of the fire place basket is such as will in no way complicate the manufacture of these particular devices, which as will be understood, are more often produced by processes of casting.

In using the improved fire place basket,

the same is brought to a position directly adjacent the opening presented between the opposite sides of the grate frame 1, whereupon the basket is lowered so that the vertical and opposed brackets 5 will be engaged over the oppositely disposed pairs of supporting lugs 2 upon the grate frame by way of the openings 5^a with following downward movement of such basket. Because of the elongated formation of the ways in the brackets 5, each of the lugs 2 of the several pairs thereof will be fully engaged and therefore, it is apparent that firm and positive connection as between these lugs and the basket 3 will be had. Hence, the outward or inward swinging of the basket with respect to the grate frame 1 will be avoided. Similarly, there will be provided a positive, firm and stable support for the fire place basket, from which it will be prevented from becoming accidentally disengaged or displaced during subsequent usage.

Obviously, the mode of engagement of the improved fire place basket with the supporting lugs of the grate frame is simple, but effectual, and because of the arrangement and elongated formation of the brackets 5, that is, as shown, said improved basket may be advantageously and successfully fitted upon or connected to any form of grate frame now prevalent in the art. Hence, the device becomes universally adaptable, irrespective of the particular design, form or make of the grate frame, and because of this, it may be readily used by a person having such fire place equipment as hereinbefore described.

Manifestly, the construction shown is capable of considerable modification, and such modification as is within the scope of my claims, I consider within the spirit of my invention.

I claim:—

1. A fire-place basket having relatively parallel vertically arranged channeled brackets formed integral with the opposite ends of the front thereof, said channels facing outwardly and being arranged in opposed relationship with respect to each other, portions of the same opening in-

wardly and marginally onto the corresponding sides of the brackets.

2. A fire-place basket having relatively parallel vertically arranged channeled brackets formed integral with the opposite ends of the front thereof, said channels facing outwardly and being arranged in opposed relationship with respect to each other adapted to receive oppositely disposed lugs therein, the channels in said brackets opening inwardly and marginally onto the lower portion of the corresponding sides of their respective brackets.

3. A fire-place basket having relatively parallel vertically disposed channeled brackets formed integral with the opposite ends of the front thereof, the channels in such brackets adapted to face the adjacent and opposite sides of a grate frame and having their upper ends closed and their lower ends opening marginally onto the inner sides of said brackets.

4. A fire-place basket having thickened pieces formed upon the opposite ends of the front thereof and disposed vertically thereof and in relative parallel relation, channeled ways formed in and extending longitudinally of said pieces adapted to face the adjacent and opposite sides of a grate frame, the lower portions of said channels opening marginally onto the inner sides of the pieces.

5. A fire place basket having longitudinally disposed channels formed in the outer faces of the opposite sides thereof, the lower portion of said channels opening onto the inner faces of said sides to provide for admission of lugs thereinto.

6. A fire place basket having channeled brackets integral with and parallel to the opposite sides of the front thereof, the lower portion of each of said brackets being cut away to provide for admission of lugs to the channels of the respective brackets, the grate portion of said basket being of a width less than the width of the front of the same.

In witness whereof I have hereunto set my hand.

WALLACE W. HANLON.
